EASEL

Laura van Poppelendam, Chicago, Ill.

Application September 9, 1935, Serial No. 39,704

5 Claims. (Cl. 248—197)

This invention relates to article supports, and more particularly to easels, especially of the type employed by artists for supporting the canvas upon which a picture is produced.

5 One of the objects of the invention is the provision of support for a canvas supporting frame at the ends thereof.

Another object of the invention is to provide an easel capable of supporting a canvas of substantially any length.

10 Another object of the invention is to provide an easel capable of a wide range of adjustment so as to be adaptable to stand firmly on level or irregular surfaces.

15 Another object of the invention is to provide an easel in which the canvas supporting frame becomes an essential element of the easel so that the frame is firmly supported by and prevented from accidental displacement from the easel.

20 Another object of the invention is to provide an easel in which no portion thereof extends above the canvas supporting frame intermediate its ends, thus affording clear and unlimited visibility above and beyond the canvas.

25 Another object of the invention is to provide an easel having the canvas supporting frame so intimately associated with and supported by the easel that the assembly may be moved as a single unit.

30 Another object of the invention is the provision of an easel which is substantial, rigid when in use, light in weight, easily assembled and disassembled, and which packs compactly for transportation.

35 With these and other objects in view, the invention consists in the combination and arrangement of parts hereinafter more particularly to be described and claimed in the appended claims, reference being had to the accompanying drawings in which,

40 Fig. 1 is a front view, in elevation, of an assembled easel according to the invention,

Fig. 2 is a side view, in elevation, of the easel,

45 Fig. 3 is a face view of the upper portion of one of the rearwardly extending legs of the easel,

Fig. 4 is an edge view of the leg portion shown in Fig. 3,

50 Fig. 5 is a plan view of one of the forwardly extending legs,

Fig. 6 is a sectional view taken on the line 6—6 of Fig. 1,

Fig. 7 is a plan view of the elements of the easel arranged and associated for carrying,

55 Figs. 8 to 17 inclusive are views illustrating

several of the many assembly arrangements of which the easel is capable,

Fig. 18 is a sectional view taken on the line 18—18 of Fig. 7, and

Fig. 19 is a sectional view taken on the line 19—19 of Fig. 7.

Referring now to the drawings, in which the reference characters designate corresponding parts throughout the several views, and particularly to Fig. 1, the reference numeral 20 denotes the usual frame or canvas stretcher which is ordinarily employed by artists for supporting, in a stretched or taut condition, the canvas upon which a picture is to be produced. The frame 20 is usually rectangular in contour, and has the canvas 21 stretched across its face, drawn down over its ends, and secured thereto by any convenient means such as tacks.

As shown in Figs. 1 and 2 there are provided for supporting the frame 20, two pairs of legs, 22, one pair extending forwardly of the frame, and the other pair extending rearwardly of the frame. The forwardly extending legs, designated by the reference numeral 22, may be made of wood or light metal, of sufficient thickness to firmly support the frame 20 without bending, and preferably tapering in width uniformly from top to bottom. The rearwardly extending legs 24 may be of the same material as the legs 22, and of similar shape, being preferably of uniform thickness and of tapering width from top to bottom. As shown in Fig. 2, and in detail in Figs. 3 and 4, the legs 24 are provided with a pair of flat prongs or tongues 25 and 26. These tongues are thin strips preferably of metal, secured to the legs 24 near the upper ends thereof. The tongue 25 is secured in any convenient manner against one face of the leg 24 such as by rivets 27, and is disposed longitudinally of the leg and extends beyond the upper end thereof any desired distance, such as a few inches. The tongue 26 is similar in width and thickness to the tongue 25, and is pivotally secured near its inner end against the face of the leg 24 opposite to that which carries the tongue 25. The pivotal mounting for the tongue 26 may be one of the rivets 27 which secures the tongue 25 to the leg, or any other suitable pivot mounting may be employed, and a spacer bushing or washer 28 may be disposed between the tongue 26 and the leg 24 upon the pivotal mounting of the tongue to provide a bearing for the tongue. Intermediate its ends, the tongue 25 is provided with a double reverse or S-shaped bend by means of which the outer portion of the tongue 25 may be disposed in a plane par-

20

55

allel to the tongue 26 and only slightly displaced therefrom. The tongues 25 and 26 are employed for securing the legs 24 to the frame 20.

A plurality of clamps 29, preferably four in number, are employed for securing the legs 22 and 24 to the frame 20. The clamp 29, as shown in detail in Fig. 6, consists of a pair of cooperating hook shaped members 30 and 31. The member 30 consists of a straight portion 32 and a hook shaped portion 33 extending substantially at right angles from one end of the straight portion integral therewith. The member 30 is of metal, and may be formed in any suitable manner, such as by casting. The space defined by the straight portion 32 and the end of the hook portion 33 should be wide enough to receive and seat the widest portion of a leg 22. The straight portion 32 is preferably rectangular in cross section, or at least is provided with a flat inner surface to engage and seat a side member of the frame 20 and a leg 22. The straight portion 32 of the clamp member 30 is provided with a bore 34 extending longitudinally therethrough from end to end, the bore being non-cylindrical in cross section, and preferably square. Cooperating with the clamp member 30 is the member 31 which has a straight portion 35 extending through and slidably within the bore 34, and a hook shaped portion 36 in opposed relation to hook portion 33 of the member 30. The straight portion 35 of the clamp member 31 has a cross sectional contour corresponding to that of the bore 34 to prevent rotation of the member 31 relative to the member 30, and is slightly smaller than bore 34 to permit free relative longitudinal movement between the two members. The end of the member 31 opposite the hook shaped portion 36 is provided with threads 38 to receive a wing nut 39.

Fig. 6 shows the manner in which the clamp 29 is employed for securing a leg 22 to the frame 20. A leg 22 is disposed against a side member of the frame 20, with the leg 22 extending longitudinally of the side member. The clamp is then placed behind the side member of the frame, with the hook shaped portion 36 inside the frame, the hook shaped portion 33 outside of the leg 22, and both hook shaped portions extending forward. When the several elements have been positioned as described above, the wing nut is rotated to draw the hook shaped portions toward each other and thus firmly clamp the leg 22 and the side member of the frame 20 therebetween.

In the preceding paragraph, the manner of employing a clamp 29 to secure a forwardly extending leg 22 to one side of the frame 20 has been described. As shown in Figs. 1 and 2, it is preferable to use two clamps to secure a forwardly extending leg to the frame, the clamps being liberally spaced to afford maximum rigidity. Figs. 1 and 2 illustrate the conventional or normal assembly of the easel, for use where it can stand upon a flat surface. The rearwardly extending legs are secured in position by rotating the tongue 26 about its pivot so that it is disposed at a substantial angle to the tongue 25, as shown in Figs. 2 and 3, and inserting the tongues between the leg 22 and the side of the frame 20. After the tongues 25 and 26 have been so disposed, the clamps 29 are tightened by rotating the wing nuts 39, to firmly clamp the forwardly extending legs 22 against the frame 20. The tongues 25 and 26 are thus firmly secured between the legs 22 and the frame 20, and by reason of the angular disposition of the tongues 25 and 26 with respect to each other, relative movement

of the rearwardly extending leg 24 with respect to the frame 20 is prevented, and the leg 24 is firmly gripped and held.

As previously stated, Fig. 7 shows the manner in which the parts of the easel are arranged and associated for carrying and for storage when not in use. In order to facilitate the carrying of the easel there is provided a handle 45. The handle is of convenient size to accommodate a human hand, and is preferably of metal, cast in the desired form, although it may be fashioned by any other of the well known metal working processes into the desired form. As shown in Figs. 18 and 19, the handle is provided at its base with outwardly extending portions 46 at the opposite ends thereof. Each of the outwardly extending portions terminates in a depending flange 47. The outwardly extending portions are preferably of sufficient length to permit a pair of the legs 22 or 24 to be disposed side by side in flat position between the depending flanges of opposed outwardly extending portions. At one end of the handle is secured a threaded stud 48, and at the other end the handle is provided with an aperture 49 preferably disposed above the outwardly extending portions 46 and having its axis longitudinally of the handle.

Cooperating with the handle 45 there is shown in Figs. 7, 18 and 19 a leg supporting strip 50 which is shown in Fig. 1 employed as a brace. The strip 50 may be of any desired material, such as wood, or metal, and in the preferred construction is of the same material as the legs 22 and 24. The strip 50 is preferably of substantially the same thickness as the legs 22 and 24, and substantially as wide, throughout its length, as the widest portion of a leg 22 or 24, although its width and thickness may be varied as desired. The strip 50 may be somewhat shorter than the legs 22 and 24, as shown in Fig. 7, but it should not exceed the legs in length. The strip 50 is provided, as shown, in Fig. 1, with two longitudinally extending slots 51 separated at their inner ends by a solid portion 52 and terminating a short distance from the ends of the strip. A metal band (Fig. 18) 53 loosely surrounds and slides upon the strip 50, and the band is provided with apertures at opposite sides thereof and in registry with one of the slots 51 in the strip 50. A member 55 having a transversely extending portion 56 at one end and threaded at the other end loosely passes through the apertures of the band 53 and receives a wing nut 57. A wing nut 58 is also provided for the threaded stud 48 carried by the handle 45.

In assembling the easel for carrying, the metal band having been previously mounted on the strip 50 and the member 55 extending through one of the slots 51 and through the apertures in band 53 and having the wing nut 57 mounted thereon, the stud 48 of the handle 45 is passed through the other slot 51 to receive the wing nut 58. When the handle 45 and member 55 have been disposed as described with respect to the strip 50 and the wing nuts have been threaded onto the stud 48 and member 55, the threaded ends of those elements may be flared or otherwise distorted to prevent removal of the wing nuts, as subsequent separation of the parts is not necessary. The legs may then be positioned for carrying between the handle 45 and the strip 50, and between the pairs of depending flanges 47. This may be accomplished by sliding the legs endwise into position so that two legs lie flat in superposed relation upon strip 50 on

each side of the stud 48 and member 55. After the legs have been so positioned the wing nut 58 is tightened to firmly clamp the legs between the strip 50 and the outwardly extending portions 46 of the handle 45 at one end thereof. Then the transversely extending portion 56 of the member 55 is inserted into the aperture 49 of the handle and the wing nut 57 is tightened to clamp the legs at the other end of the handle. It is understood that the handle is preferably clamped in a central position to provide balance of the assembly to facilitate carrying.

Previous reference has been made to the use of the strip 50 as a brace and the use of the handle 45 as a cooperating clamp. One of the ways in which those elements may be so employed is shown in Fig. 1, in which the strip extends from one of the front legs 22 to the lower portion of the frame 20, and is secured to both members. The lower end of the strip 50 extends behind the leg, and the transversely extending portion 56 of member 55 is positioned against the front of the leg so that when the wing nut 57, which is not seen in Fig. 1 is tightened, the strip 25 is firmly clamped to the leg. The other end of the strip 50 extends behind the frame 20, and the depending flanges 47 of handle 45 at the end which carries stud 48 are placed against the lower edge of frame 20 with the end portion of 30 the handle (right-hand end as viewed in Fig. 7) extending upwardly in front of the lower member of the frame 20, after which the wing nut 58, which is seen in Fig. 2 may be tightened to securely clamp the strip to the frame. Increased stability and rigidity is attained by the above described use of the strip 50.

One of the objects of the invention, as hereinbefore stated, is the provision of an easel capable of a wide range of adjustments. Figs. 8 to 40 17 inclusive show some of the numerous forms into which the elements of the easel may be assembled. Referring to Fig. 8, it will be seen that the assembly is similar to that of Fig. 2 except that the tongues 25 and 26 are disposed at opposite sides of one of the clamps 29, whereas in 45 Fig. 2 the tongues are disposed between the two clamps.

Fig. 9 shows the clamping of the frame 20 high with respect to the legs 22 and 24, so that the clamps 29 are relatively close together. The tongue 25, disposed between the frame 20 and the leg 22, passes under the upper clamp 29 obliquely thereto, and the tongue 26 similarly passes under the lower clamp 29 obliquely thereto. In 55 this arrangement the clamps 29 exert a direct clamping effect on the tongues 25 and 26, and the lower ends of the legs 22 and 24 are relatively close together, to enable the placing of the easel in a limited space, such as close to the foot of an embankment.

The arrangement shown in Fig. 10 is particularly useful in positioning the easel on the side of a hill or embankment. Instead of clamping the tongues 25 and 26 between the frame 20 and legs 22, as in Figs. 2, 8 and 9, a portion of each leg 24 intermediate its end is clamped between a leg 22 and the frame 20, so that the upper end of each leg 24 extends forwardly of the frame 20.

Fig. 11 shows an arrangement of the parts similar to that of Fig. 2, except that the forwardly extending legs 22 are supported on an elevation with respect to the lower legs, such as, on stair-steps.

Fig. 12 shows an arrangement for positioning

the frame 20 at a considerably greater angle from vertical than in the previously described figures. This is accomplished by disposing the legs 24 so that the pivoted tongues 26 are disposed above the tongues 25, instead of below the 5 tongues 25 as shown in the previously described Figs. 2, 8, 9 and 11. In this arrangement, the front and rear legs are disposed at a much greater angle with respect to each other than in those figures.

The arrangement shown in Fig. 13 combines the mild slope of the frame 20, as shown in Fig. 12, and the clamping of the leg 24 rather than the tongues 25 and 26, as shown in Fig. 10. The strip 50, handle 45 and clamp member 55 are employed as a brace between a front and a rear leg, as in Fig. 1. This arrangement is convenient for supporting the forwardly extending legs at a higher level than the rearwardly extending legs.

Fig. 14 shows an arrangement similar to that 20 of Fig. 13, except that the easel is positioned on a substantially flat surface, and the rear legs 26 are substantially vertically disposed with respect to the supporting surface.

In Fig. 15, the forwardly extending leg at one 25 end of the frame 20 is disposed higher with respect to the frame than the other forwardly extending leg, so that the legs at opposite ends of the frame may be supported at different level, such as on different steps on a flight of stairs. 30

Fig. 16 shows a disposition of the parts to enable the use of the easel on a flight of stairs similar to Fig. 15, except that legs are employed at one end of the frame 20 only, the other end of the frame resting on one of the steps of the flight 35 of stairs.

Fig. 17 shows an arrangement in which three of the four legs may be supported at substantially the same level, one of the legs, such as a rearwardly extending leg being positioned lower than 40 the other, so that one may be supported at a different level.

The invention is not to be construed as limited to the specific elements, and form and arrangement of elements and parts shown, and described 45 herein, as the said elements and parts, and the combination and arrangement of said elements and parts are capable of modification and substitution within the scope of the appended claims.

What is claimed is:

1. The combination with an article supporting frame of a pair of forwardly extending legs removably clamped to said frame at a plurality of points and a pair of rearwardly extending legs clamped between said forwardly extending legs 55 and said frame intermediate the clamping points.

2. The combination with an article supporting frame of a forwardly extending leg removably secured thereto by a plurality of spaced clamps and a rearwardly extending leg having a projecting tongue-shaped portion removably clamped between said forwardly extending leg and said frame intermediate said clamps. 60

3. In combination with an article supporting frame, a leg disposed along one end of said frame in alignment therewith, a second leg having a portion disposed between the first mentioned leg and the end of said frame, and means for securing the first mentioned leg to the end of said frame at a plurality of points. 65

4. In combination with an article supporting frame, a leg disposed along one end thereof, a second leg having a pair of angularly disposed tongues secured to the upper end thereof, said tongues being disposed between the first men- 70 75

tioned leg and the end of said frame, and means for clamping the first mentioned leg to the end of said frame with the tongues rigidly held between the first mentioned leg and the end of the frame.

5. In combination with an article supporting frame, a leg disposed along one end thereof, a second leg having a pair of tongues secured to the upper end thereof, one of said tongues being fixed with respect to said leg, the other tongue

being pivoted to said leg to provide angular adjustment of one tongue relative to the other, said tongues having their outer ends disposed between the first mentioned leg and the end of the frame, and means for clamping the first mentioned leg to the end of the frame with the tongues rigidly held between the first mentioned leg and the end of the frame.

LAURA VAN PAPPELENDAM.
